UNITED STATES PATENT OFFICE.

FRANKLIN E. ARNDT, OF GALION, OHIO, ASSIGNEE TO THE GALION IRON WORKS AND MANUFACTURING COMPANY, OF GALION, OHIO, A CORPORATION OF OHIO.

STEERING-GEAR FOR ROAD-MACHINES.

1,166,036.

Specification of Letters Patent. Patented Dec. 28, 1915.

Application filed September 1, 1915. Serial No. 48,483.

To all whom it may concern:

Be it known that I, FRANKLIN E. ARNDT, a citizen of the United States of America, residing at Galion, in the county of Crawford and State of Ohio, have invented certain new and useful Improvements in Steering-Gear for Road-Machines, of which the following is a specification.

This invention comprehends certain new and useful improvements in steering gear for road machines and relates particularly to improvements in that type of steering gear for which Letters Patent of the United States Number 1,130,471 were issued March 2, 1915. As is well known to those familiar with the operation and practical use of machines of this character, it is customary to draw the machine along the road by means of a traction engine which travels in the middle of the road to obtain the best traction effect whereas the road machine must travel at the sides of the road and means must therefore be provided, to secure the best results, whereby the line of travel of the road machine may be easily maintained regardless of the relative position of the traction engine. For this purpose, the road machine is provided with a draft pole designed to be connected to the traction engine and a relatively short tongue, and means are provided whereby the operator, standing for example upon the platform at the rear of the road machine, may manually adjust the position of the tongue relative to the draft pole, so that the desired line of draft of the road machine may be easily maintained irrespective of the angular or oblique position which is assumed by the draft pole. Difficulty has heretofore been encountered, with steering gears of this character, owing to the fact that the flexible shaft designed for manual operation under the control of the operator of the road machine and arranged to turn the tongue to the right or to the left as required, was incapable of permitting the draft pole to make very sharp turns as for example when going around a corner, it being sometimes necessary to turn the tongue through an arc of at least 300 degrees and consequently some of the parts had to be unshipped while the turn was being made and again reassembled, which manifestly was a source of inconvenience and detracted from the smooth working qualities of the machine.

The present invention aims to entirely do

away with the difficulties above referred to and to provide a novel and useful construction of flexible shaft which will insure the proper working of the parts at all times and which can be easily and cheaply manufactured, which will be durable, and which will not be likely to get out of order.

With these and other objects in view as will more fully appear as the description proceeds, the invention consists in certain constructions, arrangements and combinations of the parts that I shall hereinafter fully describe and claim.

For a full understanding of the invention reference is to be had to the following description and accompanying drawings, in which—

Figure 1 is a side elevation of so much of a road machine as is necessary to indicate the character of the machine and to impart a thorough understanding of the improvements of the present invention. Fig. 2 (Sheet 2) is a perspective view in the nature of a diagram showing the draft pole turned at a sharp angle to the main supporting frame of the machine. Fig. 3 is a plan view of portions of the steering gear hereinafter specifically referred to. Fig. 4 is a detail transverse sectional view through the worm gearing employed. Fig. 5 is a detail perspective view of the swinging bracket and its arch. Fig. 6 is a detail view of one of the shaft sections. Fig. 7 is a similar view of another section of the flexible operating shaft of the apparatus. Fig. 8 illustrates still another section of said shaft; and Fig. 9 is a detail view of a swinging arm employed.

Corresponding and like parts are referred to in the following description and designated in the different views of the accompanying drawing by like reference characters.

Referring to the drawings, the numeral 1 designates the frame bars of a road machine, 2 the draft pole which is provided at its forward end with a clevis 3 whereby it may be readily secured to the draft bar of a traction engine and 4 designates the relatively short tongue of the machine by the turning of which to the right or to the left the front ground or traveling wheels 5 are steered.

Carried by the tongue 4, as will more fully appear by reference to Patent Number 1,130,471 above mentioned, is an arcuate bar

6 to the ends of which levers 7 are pivotally connected intermediate of their ends as indicated at 8, said levers having inwardly turned hooked ends 9 to which the ends of a 5 sprocket chain 10 are connected; and secured to the other and rear ends of the levers 7 are spring tension members 11 designed, in an evident manner, to hold the chain 10 taut and compensate for any shocks. The 10 chain 10 passes over and across a pinion 12 secured to the lower end of a vertically disposed spindle 13 mounted in a gear casing 14 supported upon the pole 2 and the spindle 13 carries at its upper end a worm gear 15 15 which meshes with a worm 16 formed on or secured to a longitudinally disposed shaft section 17 which forms a member of the flexible operating shaft designated A as a whole. This shaft, as best illustrated in 20 Fig. 1, extends rearwardly over and above the frame work of the road machine and is provided at its rear end with a hand wheel 18 arranged in convenient proximity to the platform (not shown) at the rear of the 25 machine, upon which the operator stands to control not only the steering gear but the other parts of the machine, as will be clearly understood by those familiar with this class of machinery.

30 From the foregoing it will be noted that by turning the shaft 9 in the required direction, the spindle 13 will be turned and the chain 10, through the instrumentality of the spur pinion 12, will be rotated to move the chain 10 laterally and thereby cause the tongue 4 to be swung to the right or to the left as desired. By the use of the worm gearing within the casing 14 it is obvious that no 35 separate or independent locking devices are necessary to maintain the parts in their adjusted positions which is an incident of advantage as more fully set forth in my prior patent above referred to.

40 The present invention relates more particularly, as indicated at the outset of the specification, to the construction and arrangement of parts or members of the flexible shaft A, whereby the machine may be turned around relatively sharp corners with facility and without the necessity of unshipping 45 any of the parts and I shall now proceed to describe these features in detail.

50 The rearmost member or section of the flexible shaft A and to which the hand wheel 18 is fastened is designated 19 and is in the form of a rod mounted for rotation upon its longitudinal axis in a rear arch 20 and an intermediate arch 21 straddling and supported upon the arched frame bars 1 as 55 best illustrated in Fig. 2. The intermediate section or member of the shaft 9 is designated 22 and is formed of telescopic sections 23 and 24, the tubular section 23 having the section 24 extensibly mounted therein and 60 both members are so shaped as best illus-

trated in Fig. 7 as to compel them to rotate together which is of course necessary for the successful operation of the shaft. The adjoining ends of the shaft members 19 and 22 are connected together by a universal 70 joint 25 and the lower forward end of the intermediate member 22 is similarly connected as at 26 to a laterally swinging arm 27 mounted to rotate in a bracket 28 which is formed with relatively short and long 75 arms as clearly illustrated in Figs. 1, 2 and 5, and pivotally mounted eccentrically (that is, nearer one arm than the other) upon a transversely disposed bracket arch 29 secured in any desired way to the forward 80 portions of the frame bars 1. The foremost member 30 of the shaft A is likewise telescopic in nature and comprises a tubular section 31 and a solid section 32 extensibly mounted therein, a spring 33 being coiled 85 around the section 32 and received within the section 31 and exerting such a tension on the sections as to contract them or draw one within the other. This member 30 is connected to the lower end of the forwardly and downwardly inclined swinging arm 27 by means of a universal joint 34 at one end and at its other end is connected by a universal joint 35 to the short shaft section or member 17 carrying the worm 16, before referred to. 90 Preferably the arm 27 is journaled in the laterally swinging bracket 28 nearer one end of the arm than the other, as clearly shown in the drawings, whereby the forwardly and downwardly projecting portion of said 95 arm, where it is connected to the foremost member 30 of the flexible shaft A may project laterally out over the frame work of the machine, to provide a clearance so as to permit the telescopic member 30 to pass 100 under the frame, if required in the turning movement and the extensible or telescopic member 22 also co-operates in this movement of the parts, as is manifest, whereby the machine may be turned about without the necessity of unshipping any of the parts and 105 without any members binding or becoming dislocated. By providing a spring 33 within the telescopic member 30, the same tending 110 to contract or close by this means, it is held 115 properly rigid in its work and is prevented from swinging around which would render the slip joints liable to come apart.

From the foregoing description in connection with the accompanying drawings, it 120 will be seen that I have provided a very efficient as well as durable steering gear which will overcome the disadvantages set forth near the outset of the specification and by the use of which the parts will be always 125 maintained in proper operative operation to each other and without danger of binding in any way or of coming apart.

While the accompanying drawings illustrate what I believe to be the preferred em- 130

bodiment of my invention, it is to be understood that the invention is not limited thereto, but that various changes may be made in the construction, arrangement and proportions of the parts without departing from the scope of the invention as defined in the appended claims.

I claim:

1. In a road machine, steering mechanism including a draft pole, a tongue, a connection between said draft pole and tongue whereby the latter may be turned relatively to the former, an operating shaft for said connection, said shaft embodying extensible members, a rotatable arm having universal joint connection with said members and located between the same, a bracket arch, and a laterally swinging bracket mounted upon said arch and in which said arm is journaled.
2. In a road machine, steering mechanism including a draft pole, a tongue, a connection between the two whereby the tongue may be moved to different angular adjustments relative to the pole, a flexible operating shaft for said connection, said shaft embodying members each of which is constructed of telescopic sections and one of said members being provided with a spring tending to close its sections together, an arm mounted between said extensible members and having universal joint connection therewith, and a laterally swinging bracket in which said arm is mounted for rotary movement.
3. In a road machine, steering mechanism including a draft pole, a tongue, a connection between the two whereby the tongue may be moved to different oblique positions relative to the pole, a flexible operating shaft for said connection, said shaft embodying a

rear rotatable member adapted to be manually turned, supporting means for said member, an intermediate member having universal joint connection with the rear member, said intermediate member consisting of sections telescopically connected together, a forwardly and downwardly inclined arm having universal joint connection with the forward end of the intermediate member, supporting means for said arm permitting the same to be turned laterally and allowing for the rotary movement of said arm, and a forward member having universal joint connection at its rear end with the forwardly and downwardly extending end of said arm, said last named member being also constructed in telescopically arranged sections.

4. In a road machine embodying frame bars, a tongue, a draft pole and a connection between the tongue and draft pole whereby the former may be turned to different oblique positions relative to the latter, an operating shaft for said connection, said shaft embodying a plurality of members having universal joint connections between their ends, said members including a telescoping intermediate member, a telescoping forward member and an arm between said members, a bracket arch carried by the frame bars, and a bracket pivotally mounted near one side upon said arch, the arm being journaled near one end in said bracket, as and for the purpose set forth.

In testimony whereof I affix my signature in the presence of two witnesses.

FRANKLIN E. ARNDT.
